UNITED STATES PATENT OFFICE.

RICHARD W. SCHMELZ, OF BROOKLYN, NEW YORK, ASSIGNOR OF ONE-HALF
TO WILLIAM V. GEIS, OF NEW YORK, N. Y.

GARTER.

SPECIFICATION forming part of Letters Patent No. 706,855, dated August 12, 1902.

Application filed January 27, 1902. Serial No. 91,346. (No model.)

To all whom it may concern:

Be it known that I, RICHARD W. SCHMELZ, a citizen of the United States, residing at Brooklyn, in the county of Kings and State 5 of New York, have invented certain new and useful Improvements in Garters, of which the following is a full and complete specification, such as will enable those skilled in the art to which it appertains to make and use the same.

10 The object of this invention is to provide an improved garter designed for use by gentlemen, but which may be used by ladies, if desired; and with this and other objects in view the invention consists in a device of the class 15 specified constructed as hereinafter described and claimed.

In the drawings forming part of this specification, in which the separate parts of my improvement are designated by the same reference characters in each of the views, Figure 1 is a front elevation of a spring-clamp which forms a part of my improvement; Fig. 2, a similar view showing the garter cord or strap connected therewith, and Fig. 3 a similar 25 view showing the operation of the device.

In the practice of my invention I take a spring-wire and bend it to form a spring-ring *a*, which is provided at one side with a looped clamp *b*, and opposite the looped clamp *b* the 30 sides of the ring are crossed, as shown at *c*, and extend in opposite directions and are formed into oppositely-directed spring-loops *d*, consisting of side members *d*² and *d*³, the said side members *d*³ being free and the ends 35 thereof being bent in adjacent to the side members *d*² and terminating in rings or loops *e*, adjacent to the point *c* where the separate sides of the ring are crossed. I also employ a cord *f*, which may be of silk or any suitable 40 material, and this cord is passed into the spring-loops *d*, as clearly shown in Figs. 2 and 3, the opposite ends thereof being passed between the eyes or rings *e* and slipped into said loops *d*, as will be readily understood.

45 When the garter is placed on the leg in this manner, as shown in Fig. 3, the top of the stocking or a portion thereof is pulled through the spring-loop *b*, as indicated at *g*, and the said spring-loop *b* securely holds the stocking

in proper position. It will also be understood that the operation of the cord *f* when drawn through the loops *d* is to pull said loops outwardly, and thus contract the ring *a* and force the spring-loop *b* to more securely grasp and hold the stocking. I also prefer to pass 50 both ends of the cord *f* into the loops *d*, as shown in Figs. 2 and 3, and said cord may be tightened whenever desired by pulling one of said ends through one of said loops; but it will be readily understood that either end of 55 said cord may be secured to the corresponding loop and the other end passed into its loop, if desired. When the ends of the cord are passed through the loops *d*, as shown in Fig. 2, they are held therein by friction and the 60 spring action of said loops, and said loops are so formed that they securely hold said cord or the ends thereof.

This device is simple in construction and operation and comparatively inexpensive and 70 may be made of any desired material.

The cord or strap *f* is also preferably made of non-elastic material, and in this case the spring-ring *a* and the loops *d* will give all the necessary elasticity to the device, it being 75 understood that the ring *a* is free to expand and contract, and in operation the loops *d* are also drawn outwardly or inwardly, as will be readily understood.

Having thus fully described my invention, 80 what I claim as new, and desire to secure by Letters Patent, is—

1. A garter device comprising a spring-ring having an integral projecting loop at one side, said ring being open opposite said loop and 85 the sides thereof being crossed and extended and formed into oppositely-directed and independent loops which open inwardly adjacent to the point where the sides of the ring are crossed and form frictional holders, and the 90 ends of the free sides of which are curved outwardly substantially as shown and described.

2. A garter device comprising a spring-ring having an integral projecting loop at one side, said ring being open opposite said loop and 95 the sides thereof being crossed and extended and formed into oppositely-directed and independent loops which open inwardly adjacent

to the point where the sides of the ring are crossed and form frictional holders, and the ends of the free sides of which are curved outwardly, and a cord which is adapted to be
5 passed around the leg and into said loops, substantially as shown and described.

In testimony that I claim the foregoing as

my invention I have signed my name, in presence of the subscribing witnesses, this 24th day of January, 1902.

RICHARD W. SCHMELZ.
